UNITED STATES PATENT OFFICE.

EDWIN H. SWIFT, OF BROOKLYN, NEW YORK.

AIR HEATER AND RETARDER.

Application filed December 22, 1922. Serial No. 608,518.

This invention relates to an air heater and retarder.

Its object is the production of a device, by means of which heated air is supplied to the unconsumed products of combustion of the fuel of a furnace, to obtain complete combustion. A second object of the device is to provide heated air to the burning fuel of a furnace, at a velocity of inflow, by means of which the oxygen of the inflowing air will all combine with the unconsumed gases generated, and therefore not chill the bed of fuel. A third object of the invention is the production of means whereby all portions of an inflow of air to a furnace is heated before mixing with the gases generated therein. A fourth object of the invention is to prevent the escape of obnoxious gases from the combustion chamber of a furnace.

In the accompanying drawings Fig. 1 represents a side view of an exemplification of the air heater and retarder applied to a furnace; Fig. 2 shows an enlarged side view of the heater and retarder; Fig. 3 indicates a left hand side view of Fig. 2; Fig. 4 shows a section on the line 4, 4 of Fig. 3 and Fig. 5 represents a section on the line 5, 5 of Fig. 4.

The air heater and retarder comprises an induction tube, consisting of an outer portion designated in its entirety by the letter A, and the inner portion designated in its entirety by the letter B. A retarding coil designated in its entirety by the letter C, is detachably fastened within the inner portion B.

The portion A of the induction tube has formed therewith the flared or nozzle shaped inlet end 20, and the flange 21 with the openings 22 at its other end. A tapered seat 23 in the portion A extends forwardly from the flange 21. A damper 28 is located in the portion A and is supported on the spindle 29, the ends of which are journaled in the opposite sides of said portion A. An operating knob 30 is fastened to one end of the spindle 29, and an arm 31 with the extension 32 is fastened to the other end of the said spindle.

The portion B of the induction tube at one end has formed therewith the tapered end 34, and at the other end of the portion B is formed the flared or nozzle shaped outlet end 35. The tapered end 34 of the portion B is normally seated on the tapered end 23 of the portion A, and a pin 36 ex-

tends through openings in the portions A and B to lock them to each other.

The retarding coil C consists, in this instance of a core, consisting of a pair of wires 38 and 39 wound to each other, and with which is formed at one end an eye 40.

A coil, and in this instance a double threaded coil consisting of a series of rings 44 extending from said core, follow each other in a helical direction through the portion B of the induction tube. The pin 36 extends through the eye 40. The rings 44 intersect each other to form a plurality of longitudinal ducts in the coil.

Referring to Fig. 1 a furnace is indicated in its entirety by the letter F and comprises the combustion chamber 45, the grate 46, the front wall 47, the rear wall 48 and the ash pit 49. The furnace door 50 has fastened thereto the air heater and retarder. The portion A is located on the outside of said door with the flange 21 fastened thereto by means of the screws 57, and the portion B extends from the inside face of the door 50, to the inside face of the wall 47, not to be in the direct heat zone of the chamber 45, and which prevents the heater and retarder being injured by the heat of the furnace.

To use the air heater and retarder, the damper 28 in the portion A of the induction tube, is located to permit the required volume of air to flow into the chamber 45 at the required velocity. As the air flows through the portion B of the induction tube a portion is retarded and twirled in various directions by means of the coil C and at the same time a direct flow is given to another portion of the air flowing through the tube. By this means the air is thoroughly heated throughout all portions thereof, before it enters the furnace and is in proper condition for the combination of its oxygen with the unconsumed gases of the products of combustion. By this means perfect combustion is obtained with a great saving of fuel and obnoxious gases are prevented from escaping from the furnace.

Having described my invention, what I desire to secure by Letters Patent and claim is:

In an air heater and retarder the combination of an induction tube comprising an outer portion with a flange at one end thereof and a tapered seat at said end, an inner portion for said tube with a tapered end seated in the tapered seat of the outer portion, a detachable pin extending through

both tubes at their junction, a damper in the said outer portion of the induction tube, a coil in the tube, said coil comprising a core with a series of rings extending therefrom in a helical curve through the tube, said core having an eye at one end thereof, said eye engaged by said detachable pin to

enable the easy withdrawal of said core from the tube.

Signed at the borough of Manhattan, city 10 of New York, in the county of New York and State of New York this 2nd day of December A. D. 1922.

EDWIN H. SWIFT.
